MULTILAYER COIL COMPONENT**CROSS-REFERENCE TO RELATED APPLICATION**

This application claims benefit of priority to Japanese Patent Application No. 2019-097637, filed May 24, 2019, the entire content of which is incorporated herein by reference.

BACKGROUND**Technical Field**

The present disclosure relates to a multilayer coil component.

Background Art

In response to the increasing communication speed and miniaturization of electronic devices in recent years, it is demanded that multilayer inductors have satisfactory radio-frequency characteristics in a high-frequency band (for example, a GHz band located at frequencies greater than or equal to 60 GHz). As an example of a multilayer coil component, Japanese Unexamined Patent Application Publication No. 09-129447 discloses a multilayer inductor in which the stacking direction of insulating members and the axial direction of the coil are parallel to the mounting surface of the multilayer inductor. In FIG. 2 of Japanese Unexamined Patent Application Publication No. 09-129447, a configuration is disclosed in which the coil conductors are 1/2 pattern coil conductors (pattern in which two coil conductors are stacked to form one turn of the coil).

In the multilayer inductor disclosed in Japanese Unexamined Patent Application Publication No. 09-129447, outer electrodes are formed by performing sputtering, vacuum deposition or the like on the two end portions of a multilayer body of the multilayer inductor. However, the multilayer inductor is thought to have poor mountability due to the outer electrodes not being disposed on the mounting surface of the multilayer inductor.

Accordingly, consideration has been given to providing the outer electrodes on the mounting surface in order to improve the mountability of the multilayer inductor. However, since stray capacitances are generated between the outer electrodes and the coil conductors when the outer electrodes are provided on the mounting surface, there is a risk that these stray capacitances will lead to deterioration of the radio-frequency characteristics of the multilayer inductor.

SUMMARY

Accordingly, the present disclosure provides a multilayer coil component that has excellent mountability and excellent radio-frequency characteristics.

A multilayer coil component according to a preferred embodiment of the present disclosure includes a multilayer body that is formed by stacking a plurality of insulating layers on top of one another in a length direction and that has a coil built into the inside thereof; and a first outer electrode and a second outer electrode that are electrically connected to the coil. The coil is formed by a plurality of coil conductors stacked in the length direction together with the insulating layers being electrically connected to each other. The multilayer body has a first end surface and a second end

surface, which face each other in the length direction, a first main surface and a second main surface, which face each other in a height direction perpendicular to the length direction, and a first side surface and a second side surface, which face each other in a width direction perpendicular to the length direction and the height direction. The first outer electrode extends along and covers part of the first end surface and part of the first main surface. The second outer electrode extends along and covers part of the second end surface and part of the first main surface. The first main surface is a mounting surface. A stacking direction of the multilayer body and an axial direction of the coil are parallel to the first main surface. The number of coil conductors that are stacked in order to form one turn of the coil is two. The coil conductors each include a line portion and a land portion arranged at an end of the line portion, and the land portions of coil conductors that are adjacent to each other in the stacking direction are connected to each other through via conductors. In a plan view from the width direction, the land portions are disposed in an upper half of the multilayer body on the opposite side from the first main surface.

According to the preferred embodiment of the present disclosure, a multilayer coil component can be provided that has excellent mountability and excellent radio-frequency characteristics.

Other features, elements, characteristics and advantages of the present disclosure will become more apparent from the following detailed description of preferred embodiments of the present disclosure with reference to the attached drawings.

BRIEF DESCRIPTION OF THE DRAWINGS

FIG. 1 is a perspective view schematically illustrating an example of a multilayer coil component according to an embodiment of the present disclosure;

FIG. 2A is a side view of the multilayer coil component illustrated in FIG. 1, FIG. 2B is a front view of the multilayer coil component illustrated in FIG. 1, and FIG. 2C is a bottom view of the multilayer coil component illustrated in FIG. 1;

FIG. 3 is an exploded perspective view schematically illustrating an example of a multilayer body of the multilayer coil component;

FIG. 4 is an exploded plan view schematically illustrating the example of the multilayer body of the multilayer coil component;

FIG. 5 is a sectional view schematically illustrating an example of the internal structure of the multilayer body of the multilayer coil component;

FIG. 6A is a schematic diagram illustrating the repeating shape of coil conductors of a test piece of example 1 and FIG. 6B is a schematic diagram illustrating the repeating shape of coil conductors of a test piece of comparative example 1;

FIG. 7 is a diagram schematically illustrating a method of measuring the transmission coefficient S21; and

FIG. 8 is a graph illustrating the transmission coefficient S21 in example 1 and comparative example 1.

DETAILED DESCRIPTION

Hereafter, a multilayer coil component according to an embodiment of the present disclosure will be described. However, the present disclosure is not limited to the following embodiment and the present disclosure can be applied with appropriate modifications within a range that does not alter the gist of the present disclosure. Combina-

tions consisting of two or more desired configurations among the configurations described below are also included in the scope of the present disclosure.

FIG. 1 is a perspective view schematically illustrating an example of a multilayer coil component according to an embodiment of the present disclosure. FIG. 2A is a side view of the multilayer coil component illustrated in FIG. 1, FIG. 2B is a front view of the multilayer coil component illustrated in FIG. 1, and FIG. 2C is a bottom view of the multilayer coil component illustrated in FIG. 1.

A multilayer coil component 1 illustrated in FIGS. 1, 2A, 2B, and 2C includes a multilayer body 10, a first outer electrode 21, and a second outer electrode 22. The multilayer body 10 has a substantially rectangular parallelepiped shape having six surfaces. The configuration of the multilayer body 10 will be described later, but the multilayer body 10 is formed by stacking a plurality of insulating layers on top of one another in a length direction and has a coil built into the inside thereof. The first outer electrode 21 and the second outer electrode 22 are electrically connected to the coil.

In the multilayer coil component 1 and the multilayer body 10 of the embodiment of the present disclosure, a length direction, a height direction, and a width direction are respectively an x direction, a y direction, and a z direction in FIG. 1. Here, the length direction (x direction), the height direction (y direction), and the width direction (z direction) are perpendicular to each other.

As illustrated in FIGS. 1, 2A, 2B, and 2C, the multilayer body 10 has a first end surface 11 and a second end surface 12, which face each other in the length direction (x direction), a first main surface 13 and a second main surface 14, which face each other in the height direction (y direction) perpendicular to the length direction, and a first side surface 15 and a second side surface 16, which face each other in the width direction (z direction) perpendicular to the length direction and the height direction.

As illustrated in FIG. 1, in the multilayer body 10, a coil axis A is assumed that is parallel to the length direction (x direction) and penetrates from the first end surface 11 to the second end surface 12. The direction in which the coil axis A extends is the axial direction of the coil that is built into the multilayer body 10. The axial direction of the coil and the stacking direction of the multilayer body 10 are parallel to the first main surface 13, which is a mounting surface.

Although not illustrated in FIG. 1, corner portions and edge portions of the multilayer body 10 are preferably rounded. The term "corner portion" refers to a part of the multilayer body 10 where three surfaces intersect and the term "edge portion" refers to a part of the multilayer body 10 where two surfaces intersect.

The first outer electrode 21 is arranged so as to cover part of the first end surface 11 of the multilayer body 10 as illustrated in FIGS. 1 and 2B and so as to extend from the first end surface 11 and cover part of the first main surface 13 of the multilayer body 10, as illustrated in FIGS. 1 and 2C. As illustrated in FIG. 2B, the first outer electrode 21 covers a region of the first end surface 11 that includes the edge portion that intersects the first main surface 13, but does not cover a region of the first end surface 11 that includes the edge portion that intersects the second main surface 14. Therefore, the first end surface 11 is exposed in the region including the edge portion that intersects the second main surface 14. In addition, the first outer electrode 21 does not cover the second main surface 14.

In FIG. 2B, the height of the part of the first outer electrode 21 that covers the first end surface 11 of the multilayer body 10 is constant, but the shape of the first outer

electrode 21 is not particularly limited so long as the first outer electrode 21 covers part of the first end surface 11 of the multilayer body 10. For example, the first outer electrode 21 may have an arch-like shape that increases in height from the ends thereof toward the center thereof on the first end surface 11 of the multilayer body 10. In addition, in FIG. 2C, the length of the part of the first outer electrode 21 that covers the first main surface 13 of the multilayer body 10 is constant, but the shape of the first outer electrode 21 is not particularly limited so long as the first outer electrode 21 covers part of the first main surface 13 of the multilayer body 10. For example, the first outer electrode 21 may have an arch-like shape that increases in length from the ends thereof toward the center thereof on the first main surface 13 of the multilayer body 10.

As illustrated in FIGS. 1 and 2A, the first outer electrode 21 may be additionally arranged so as to extend from the first end surface 11 and the first main surface 13 and cover part of the first side surface 15 and part of the second side surface 16. In this case, as illustrated in FIG. 2A, the parts of the first outer electrode 21 covering the first side surface 15 and the second side surface 16 are preferably formed in a diagonal shape relative to both the edge portion that intersects the first end surface 11 and the edge portion that intersects the first main surface 13. However, the first outer electrode 21 does not have to be arranged so as to cover part of the first side surface 15 and part of the second side surface 16.

The second outer electrode 22 is arranged so as to cover part of the second end surface 12 of the multilayer body 10 and so as to extend from the second end surface 12 and cover part of the first main surface 13 of the multilayer body 10. Similarly to the first outer electrode 21, the second outer electrode 22 covers a region of the second end surface 12 that includes the edge portion that intersects the first main surface 13, but does not cover a region of the second end surface 12 that includes the edge portion that intersects the second main surface 14. Therefore, the second end surface 12 is exposed in the region including the edge portion that intersects the second main surface 14. In addition, the second outer electrode 22 does not cover the second main surface 14.

Similarly to the first outer electrode 21, the shape of the second outer electrode 22 is not particularly limited so long as the second outer electrode 22 covers part of the second end surface 12 of the multilayer body 10. For example, the second outer electrode 22 may have an arch-like shape that increases in height from the ends thereof toward the center thereof on the second end surface 12 of the multilayer body 10. Furthermore, the shape of the second outer electrode 22 is not particularly limited so long as the second outer electrode 22 covers part of the first main surface 13 of the multilayer body 10. For example, the second outer electrode 22 may have an arch-like shape that increases in length from the ends thereof toward the center thereof on the first main surface 13 of the multilayer body 10.

Similarly to the first outer electrode 21, the second outer electrode 22 may be additionally arranged so as to extend from the second end surface 12 and the first main surface 13 and cover part of the first side surface 15 and part of the second side surface 16. In this case, the parts of the second outer electrode 22 covering the first side surface 15 and the second side surface 16 are preferably formed in a diagonal shape relative to both the edge portion that intersects the second end surface 12 and the edge portion that intersects the first main surface 13. However, the second outer elec-

trode 22 does not have to be arranged so as to cover part of the first side surface 15 and part of the second side surface 16.

The first outer electrode 21 and the second outer electrode 22 are arranged in the manner described above, and therefore the first main surface 13 of the multilayer body 10 serves as a mounting surface when the multilayer coil component 1 is mounted on a substrate.

Although the size of the multilayer coil component 1 according to the embodiment of the present disclosure is not particularly limited, the multilayer coil component 1 is preferably the 0603 size, the 0402 size, or the 1005 size.

In the case where the multilayer coil component 1 according to the embodiment of the present disclosure is the 0603 size, the length of the multilayer body 10 (length indicated by double-headed arrow L_1 in FIG. 2A) preferably lies in a range from 0.57 mm to 0.63 mm. In the case where the multilayer coil component 1 according to the embodiment of the present disclosure is the 0603 size, the width of the multilayer body 10 (length indicated by double-headed arrow W_1 in FIG. 2C) preferably lies in a range from 0.27 mm to 0.33 mm. In the case where the multilayer coil component 1 according to the embodiment of the present disclosure is the 0603 size, the height of the multilayer body 10 (length indicated by double-headed arrow T_1 in FIG. 2B) preferably lies in a range from 0.27 mm to 0.33 mm.

In the case where the multilayer coil component 1 according to the embodiment of the present disclosure is the 0603 size, the length of the multilayer coil component 1 (length indicated by double arrow L_2 in FIG. 2A) preferably lies in a range from 0.57 mm to 0.63 mm. In the case where the multilayer coil component 1 according to the embodiment of the present disclosure is the 0603 size, the width of the multilayer coil component 1 (length indicated by double-headed arrow W_2 in FIG. 2C) preferably lies in a range from 0.27 mm to 0.33 mm. In the case where the multilayer coil component 1 according to the embodiment of the present disclosure is the 0603 size, the height of the multilayer coil component 1 (length indicated by double-headed arrow T_2 in FIG. 2B) preferably lies in a range from 0.27 mm to 0.33 mm.

In the case where the multilayer coil component 1 according to the embodiment of the present disclosure is the 0603 size, the length of the part of the first outer electrode 21 that covers the first main surface 13 of the multilayer body 10 (length indicated by double-headed arrow E_1 in FIG. 2C) preferably lies in a range from 0.12 mm to 0.22 mm. Similarly, the length of the part of the second outer electrode 22 that covers the first main surface 13 of the multilayer body 10 preferably lies in a range from 0.12 mm to 0.22 mm. Additionally, in the case where the length of the part of the first outer electrode 21 that covers the first main surface 13 of the multilayer body 10 and the length of the part of the second outer electrode 22 that covers the first main surface 13 of the multilayer body 10 are not constant, it is preferable that the lengths of the longest parts thereof lie within the above-described range.

In the case where the multilayer coil component 1 according to the embodiment of the present disclosure is the 0603 size, the height of the part of the first outer electrode 21 that covers the first end surface 11 of the multilayer body 10 (length indicated by double-headed arrow E_2 in FIG. 2B) preferably lies in a range from 0.10 mm to 0.20 mm. Similarly, the height of the part of the second outer electrode 22 that covers the second end surface 12 of the multilayer body 10 preferably lies in a range from 0.10 mm to 0.20 mm. In this case, stray capacitances arising from the outer elec-

trodes 21 and 22 can be reduced. In the case where the height of the part of the first outer electrode 21 that covers the first end surface 11 of the multilayer body 10 and the height of the part of the second outer electrode 22 that covers the second end surface 12 of the multilayer body 10 are not constant, it is preferable that the heights of the highest parts thereof lie within the above-described range.

In the case where the multilayer coil component 1 according to the embodiment of the present disclosure is the 0402 size, the length of the multilayer body 10 preferably lies in a range from 0.38 mm to 0.42 mm and the width of the multilayer body 10 preferably lies in a range from 0.18 mm to 0.22 mm. In the case where the multilayer coil component 1 according to the embodiment of the present disclosure is the 0402 size, the height of the multilayer body 10 preferably lies in a range from 0.18 mm to 0.22 mm.

In the case where the multilayer coil component 1 according to the embodiment of the present disclosure is the 0402 size, the length of the multilayer coil component 1 preferably lies in a range from 0.38 mm to 0.42 mm. In the case where the multilayer coil component 1 according to the embodiment of the present disclosure is the 0402 size, the width of the multilayer coil component 1 preferably lies in a range from 0.18 mm to 0.22 mm. In the case where the multilayer coil component 1 according to the embodiment of the present disclosure is the 0402 size, the height of the multilayer coil component 1 preferably lies in a range from 0.18 mm to 0.22 mm.

In the case where the multilayer coil component 1 according to the embodiment of the present disclosure is the 0402 size, the length of the part of the first outer electrode 21 that covers the first main surface 13 of the multilayer body 10 preferably lies in a range from 0.08 mm to 0.15 mm. Similarly, the length of the part of the second outer electrode 22 that covers the first main surface 13 of the multilayer body 10 preferably lies in a range from 0.08 mm to 0.15 mm.

In the case where the multilayer coil component 1 according to the embodiment of the present disclosure is the 0402 size, the height of the part of the first outer electrode 21 that covers the first end surface 11 of the multilayer body 10 preferably lies in a range from 0.06 mm to 0.13 mm. Similarly, the height of the part of the second outer electrode 22 that covers the second end surface 12 of the multilayer body 10 preferably lies in a range from 0.06 mm to 0.13 mm. In this case, stray capacitances arising from the outer electrodes 21 and 22 can be reduced.

In the case where the multilayer coil component 1 according to the embodiment of the present disclosure is the 1005 size, the length of the multilayer body 10 preferably lies in a range from 0.95 mm to 1.05 mm and the width of the multilayer body 10 preferably lies in a range from 0.45 mm to 0.55 mm. In the case where the multilayer coil component 1 according to the embodiment of the present disclosure is the 1005 size, the height of the multilayer body 10 preferably lies in a range from 0.45 mm to 0.55 mm.

In the case where the multilayer coil component 1 according to the embodiment of the present disclosure is the 1005 size, the length of the multilayer coil component 1 preferably lies in a range from 0.95 mm to 1.05 mm. In the case where the multilayer coil component 1 according to the embodiment of the present disclosure is the 1005 size, the width of the multilayer coil component 1 preferably lies in a range from 0.45 mm to 0.55 mm. In the case where the multilayer coil component 1 according to the embodiment of the present disclosure is the 1005 size, the height of the multilayer coil component 1 preferably lies in a range from 0.45 mm to 0.55 mm.

In the case where the multilayer coil component 1 according to the embodiment of the present disclosure is the 1005 size, the length of the part of the first outer electrode 21 that covers the first main surface 13 of the multilayer body 10 preferably lies in a range from 0.20 mm to 0.38 mm. Similarly, the length of the part of the second outer electrode 22 that covers the first main surface 13 of the multilayer body 10 preferably lies in a range from 0.20 mm to 0.38 mm.

In the case where the multilayer coil component 1 according to the embodiment of the present disclosure is the 1005 size, the height of the part of the first outer electrode 21 that covers the first end surface 11 of the multilayer body 10 preferably lies in a range from 0.15 mm to 0.33 mm. Similarly, the height of the part of the second outer electrode 22 that covers the second end surface 12 of the multilayer body 10 preferably lies in a range from 0.15 mm to 0.33 mm. In this case, stray capacitances arising from the outer electrodes 21 and 22 can be reduced.

In the multilayer coil component 1 according to the embodiment of the present disclosure, the number of coil conductors that are stacked in order to form one turn of the coil is two. In addition, each coil conductor includes a line portion and land portions disposed at the ends of the line portion. The line portions of coil conductors that are adjacent to each other in the stacking direction are connected to each other by via conductors, and in a plan view from the width direction, the land portions are located in an upper half of the multilayer body 10 on the opposite side from the first main surface 13.

FIG. 3 is an exploded perspective view schematically illustrating an example of the multilayer body 10 of the multilayer coil component 1 illustrated in FIG. 1 and FIG. 4 is an exploded plan view schematically illustrating the example of the multilayer body 10 of the multilayer coil component 1.

As illustrated in FIGS. 3 and 4, the multilayer body 10 includes insulating layers 31b and 31c, which are for forming one turn of the coil, as insulating layers 31 disposed between the coil conductors. Coil conductors 32b and 32c and via conductors 33b and 33c are respectively provided on and in the insulating layers 31b and 31c. The multilayer body 10 is formed by stacking these insulating layers in the length direction (x direction). The direction in which the plurality of insulating layers of the multilayer body 10 are stacked is called the stacking direction.

The coil conductors 32b and 32c are respectively provided on main surfaces of the insulating layers 31b and 31c and are stacked together with the insulating layers 31b and 31c. The two coil conductors 32b and 32c together form one turn of the coil and the coil conductors 32b and 32c are repeatedly stacked as one unit (one turn). In other words, two coil conductors are stacked in order to form one turn of the coil. In FIGS. 3 and 4, a repeating unit that forms one turn is indicated by the region surrounded by a broken line.

The coil conductors used to form one turn of the coil each include a line portion and land portions disposed at the ends of the line portion. Each coil conductor 32b includes a line portion 36b and two land portions 37b and each coil conductor 32c includes a line portion 36c and two land portions 37c. One of the land portions 37b of the coil conductor 32b is connected a land portion 37c of the adjacent coil conductor 32c by a via conductor 33b or a via conductor 33c.

The land portions are disposed in the upper half of the multilayer body 10 on the opposite side from the first main surface 13. The parts that will form the first main surface 13 of the multilayer body 10 are illustrated as sides 38b and 38c of the insulating layers 31b and 31c illustrated in FIG. 4.

Sides 39b and 39c, which are on the opposite side from the sides 38b and 38c, are parts that will form the second main surface 14 of the multilayer body 10. In FIG. 4, the upper half of the multilayer body 10 on the opposite side from the first main surface 13 refers to the area of the multilayer body 10 that is on the side near the sides 39b and 39c, which will form the second main surface 14 of the multilayer body 10, relative to a center line M between the sides 38b and 38c, which will form the first main surface 13 of the multilayer body 10, and the sides 39b and 39c, which will form the second main surface 14 of the multilayer body 10. In FIG. 4, it is illustrated that the land portions 37b and 37c of the coil conductors 32 are disposed in the area near the sides 39b and 39c, which will form the second main surface 14 of the multilayer body 10.

In this specification, the land portions that are disposed in the upper half of the multilayer body 10 on the opposite side from the first main surface 13 are land portions for connecting coil conductors that are adjacent to each other in the stacking direction to each other using via conductors. As will be described later, the land portions that are to be connected to the connection conductors are provided in the coil conductor 32a provided on the insulating layer 31a and the coil conductor 32d provided on the insulating layer 31d, and the land portions that are to be connected to connection conductors do not have to be disposed in the upper half of the multilayer body 10 on the opposite side from the first main surface 13.

As described above, when one turn of the coil is formed by two coil conductors, the respective line portions 36b and 36c of adjacent coil conductors 32b and 32c do not face each other via an insulating layer. Therefore, a stray capacitance generated between the coil conductors is small and a multilayer coil component that has excellent radio-frequency characteristics can be realized.

Since the first main surface 13 of the multilayer body 10 serves as the mounting surface and the first outer electrode 21 and the second outer electrode 22 are provided on the first main surface 13 of the multilayer body 10, an electric field is generated in a region of the multilayer body 10 near the first main surface 13 when power is supplied to the multilayer coil component 1. FIG. 5 is a sectional view schematically illustrating an example of the internal structure of the multilayer body 10 of the multilayer coil component 1 and the position at which the electric field is generated is indicated by an arrow F in FIG. 5. FIG. 5 illustrates insulating layers, coil conductors, connection conductors, and a stacking direction of the multilayer body 10 in a schematic manner, and the actual shapes, connections, and so forth are not depicted with strict accuracy. For example, the coil conductors are connected to each other by via conductors.

Since the land portions of coil conductors have larger surface areas than the line portions of coil conductors, there is a greater effect from stray capacitances and the radio-frequency characteristics are more greatly deteriorated when land portions having a large surface area intersect the electric field. Accordingly, stray capacitances produced due to the effect of the electric field generated in the area of the multilayer body 10 near the first main surface 13 can be reduced by disposing the land portions of the coil conductors in the upper half of the multilayer body 10 on the opposite side from the first main surface 13 and in this way a multilayer coil component having excellent radio-frequency characteristics can be realized.

The multilayer coil component 1 according to the embodiment of the present disclosure has both excellent mount-

ability and excellent radio-frequency characteristics. The radio-frequency characteristics are particularly excellent in a high-frequency band (in particular, band from 30 GHz to 80 GHz). Specifically, the transmission coefficient **S21** at 40 GHz preferably lies in a range from -1 dB to 0 dB, the transmission coefficient **S21** at 50 GHz preferably lies in a range from -2 dB to 0 dB, and the transmission coefficient at 60 GHz preferably lies in a range from -4 dB to 0 dB. The transmission coefficient **S21** is obtained from the ratio of the power of a transmitted signal to the power of an input signal. The transmission coefficient **S21** is basically a dimensionless quantity, but is usually expressed in dB using the common logarithm. When the above conditions are satisfied, for example, the multilayer coil component **1** can be suitably used in a bias tee circuit inside an optical communication circuit.

Furthermore, the number of stacked coil conductors **32** preferably lies in a range from 40 to 60. If the number of stacked coil conductors **32** is less than 40, the stray capacitances will become larger and the transmission coefficient **S21** will decrease. If the number of stacked coil conductors **32** exceeds 60, the direct current resistance (Rdc) will become large. The number of stacked coil conductors **32** includes both the number of stacked coil conductors **32** for forming single turns of the coil (coil conductors **32b** and coil conductors **32c**) and the number of stacked coil conductors **32** for realizing positional adjustment (coil conductor **32a** and coil conductor **32d**).

Furthermore, a distance **D** between adjacent coil conductors **32** in the stacking direction (refer to FIG. 5) preferably lies in a range from 3 μm to 10 μm . In this way, the number of turns of the coil can be increased. As a result, the impedance is increased and the transmission coefficient **S21** in a high-frequency band is also increased. The distance **D** between coil conductors **32** that are adjacent to each other in the stacking direction means the shortest distance in the stacking direction between coil conductors **32** that are connected to each other by a via conductor. Therefore, the distance **D** between coil conductors **32** that are adjacent to each other in the stacking direction and the distance between coil conductors **32** that are involved in generation of stray capacitances are not necessarily the same.

Furthermore, the length of the region in which the coil conductors **32** are arranged in the stacking direction preferably lies in a range from 85% to 95% the length of the multilayer body **10**. Here, a length **L₃** of the region in which the coil conductors **32** are arranged in the stacking direction (refer to FIG. 5) is the distance in the stacking direction from the coil conductor **32** that is connected to the first outer electrode **21** via a first connection conductor **41** to the coil conductor **32** that is connected to the second outer electrode **22** via a second connection conductor **42** (including the thicknesses of the coil conductors **32**). In the case where the length **L₃** of the region in which the coil conductors **32** are arranged is smaller than 85% of the length **L₁** of the multilayer body **10**, the radio-frequency characteristics of the multilayer coil component **1** may deteriorate due to the electrostatic capacitance of the coil becoming larger. In the case where the length **L₃** of the region in which the coil conductors **32** are arranged is greater than 95% of the length **L₁** of the multilayer body **10**, the radio-frequency characteristics of the multilayer coil component **1** may deteriorate due to the stray capacitances generated between the coil and the first outer electrode **21** and the second outer electrode **22** becoming larger. Therefore, the radio-frequency characteristics of the multilayer coil component **1** are further improved when the length **L₃** of the region in which coil

conductors **32** are arranged in the multilayer coil component **1** lies within the above-described range.

Next, other parts of the multilayer body **10** will be described while referring once again to FIGS. 3 and 4. The multilayer body **10** includes insulating layers **35a1**, **35a2**, **35a3**, and **35a4** as insulating layers **35a** located around the first connection conductor **41** and insulating layers **35b₁**, **35b₂**, **35b₃**, and **35b₄** as insulating layers **35b** located around the second connection conductor **42**.

Via conductors **33g** are provided in the insulating layers **35a1**, **35a2**, **35a3**, and **35a4**. The via conductors **33g** are connected together and form the first connection conductor **41**. Via conductors **33h** are provided in the insulating layers **35b₁**, **35b₂**, **35b₃**, and **35b₄**. The via conductors **33h** are connected together and form the second connection conductor **42**. The via conductors **33g** forming the first connection conductor **41** and the via conductors **33h** forming the second connection conductor **42** are both located on the first main surface **13** side (mounting surface side) of the multilayer body **10**.

The insulating layer **31a** is provided between the insulating layer **35a₄** and the insulating layer **31b** and the coil conductor **32a** and the via conductor **33a**, which are for connecting the via conductors **33g**, which form the first connection conductor **41**, and the coil conductor **32b** to each other, are provided on and in the insulating layer **31a**. The coil conductor **32a** includes a line portion **36a** located between two land portions **37a** and is connected between one land portion **37b**, which is connected to the via conductors **33g** disposed on the first main surface **13** side of the multilayer body **10**, and the other land portion **37b**, which is disposed on the second main surface **14** side of the multilayer body **10** and is connected to the land portion **37b** of the coil conductor **32b** by the via conductor **33a**.

Similarly, the insulating layer **31d** is provided between the insulating layer **35b₄** and the insulating layer **31c** and the coil conductor **32d** and a via conductor **33d**, which are for connecting the via conductors **33h** that form the second connection conductor **42** and the coil conductor **32c** to each other, are provided on and in the insulating layer **31d**. The coil conductor **32d** includes a line portion **36d** located between two land portion **37d** and is connected between one land portion **37d**, which is disposed on the second main surface **14** side of the multilayer body **10** and is connected to the land portion **37c** of the coil conductor **32c** by the via conductor **33c**, and the other land portion **37d**, which is connected to the via conductors **33h** disposed on the first main surface **13** side of the multilayer body **10**.

The via conductors **33a**, **33b**, **33c**, and **33d** are provided so as to respectively penetrate through the insulating layers **31a**, **31b**, **31c**, and **31d** in the stacking direction (x direction in FIG. 3).

The thus-configured insulating layers **31a**, **31b**, **31c**, and **31d** are stacked on top of one another in the x direction as illustrated in FIG. 3. Thus, the coil conductors **32a**, **32b**, **32c**, and **32d** are electrically connected to each other by the via conductors **33a**, **33b**, **33c**, and **33d**. As a result, a solenoid coil having a coil axis that extends in the x direction is formed inside the multilayer body **10**.

The first connection conductor **41** and the second connection conductor **42** are exposed at the two end surfaces **11** and **12** of the multilayer body **10**. The first connection conductor **41** is connected between the first outer electrode **21** and the coil conductor **32a** that faces the first outer electrode **21** inside the multilayer body **10**. In addition, the second connection conductor **42** is connected between the

11

second outer electrode 22 and the coil conductor 32d that faces the second outer electrode 22.

As illustrated in FIG. 5, the multilayer coil component 1 includes the multilayer body 10 in which a plurality of insulating layers 31 are stacked on top of one another and that has a coil built into the inside thereof. The coil is formed by electrically connecting a plurality of coil conductors 32, which are stacked together with the insulating layers 31, to one another. The stacking direction of the multilayer body 10 and the axial direction of the coil (coil axis A illustrated in FIG. 5) are parallel to the first main surface 13, which is the mounting surface.

In the multilayer coil component 1 illustrated in FIG. 5, the first outer electrode 21 and the coil conductor 32a that faces the first outer electrode 21 are connected to each other by the first connection conductor 41 in a straight line and the second outer electrode 22 and the coil conductor 32d that faces the second outer electrode 22 are connected to each other by the second connection conductor 42 in a straight line. The first connection conductor 41 and the second connection conductor 42 are connected to the respective coil conductors 32a and 32d at the parts of the coil conductors 32a and 32d that are closest to the first main surface 13, which is the mounting surface. The first connection conductor 41 and the second connection conductor 42 overlap the coil conductors 32 in a plan view from the stacking direction and are positioned closer to the first main surface 13, which is the mounting surface, than the coil axis. Since the first connection conductor 41 and the second connection conductor 42 are both connected to the coil conductors 32a and 32d at the parts of the coil conductors 32a and 32d that are closest to the mounting surface, the outer electrodes 21 and 22 can be reduced in size and the radio-frequency characteristics can be improved.

The repeating shape of the coil conductors is not particularly limited and may be a substantially circular shape or may be a substantially polygonal shape. In the case where the repeating shape of the coil conductors is a polygonal shape, the coil diameter is the diameter of an area-equivalent circle of the polygonal shape and the coil axis is an axis that passes through the center of the polygonal shape and is parallel to the length direction.

In the case where the multilayer coil component 1 according to the embodiment of the present disclosure is the 0603 size, the coil diameter preferably lies in a range from 50 μm to 100 μm .

In the case where the multilayer coil component 1 according to the embodiment of the present disclosure is the 0402 size, the coil diameter preferably lies in a range from 30 μm to 70 μm .

In the case where the multilayer coil component 1 according to the embodiment of the present disclosure is the 1005 size, the coil diameter preferably lies in a range from 80 μm to 170 μm .

The line width of the line portions in a plan view from the stacking direction is not particularly limited but is preferably in a range from 10% to 30% of the width of the multilayer body 10. When the line width of the line portions is less than 10% of the width of the multilayer body 10, the direct-current resistance Rdc may become large. On the other hand, when the line width of the line portions exceeds 30% of the width of the multilayer body 10, the electrostatic capacitance of the coil may become large and the radio-frequency characteristics may be degraded.

In the case where the multilayer coil component 1 according to the embodiment of the present disclosure is the 0603

12

size, the line width of the line portions preferably lies in a range from 30 μm to 90 μm and more preferably lies in a range from 30 μm to 70 μm .

In the case where the multilayer coil component 1 according to the embodiment of the present disclosure is the 0402 size, the line width of the line portions preferably lies in a range from 20 μm to 60 μm and more preferably lies in a range from 20 μm to 50 μm .

In the case where the multilayer coil component 1 according to the embodiment of the present disclosure is the 1005 size, the line width of the line portions preferably lies in a range from 50 μm to 150 μm and more preferably lies in a range from 50 μm to 120 μm .

The coil diameter in a plan view from the stacking direction preferably lies in a range from 15% to 40% of the width of the multilayer body 10.

It is preferable that the first connection conductor 41 and the second connection conductor 42 be provided inside the multilayer body 10 of the multilayer coil component 1. The shapes of the first connection conductor 41 and the second connection conductor 42 are not especially restricted, but it is preferable that the first connection conductor 41 and the second connection conductor 42 be each connected in a straight line between an outer electrode and a coil conductor. By connecting the first connection conductor 41 and the second connection conductor 42 from the coil conductors 32 to the outer electrodes 21 and 22 in straight lines, lead out portions can be simplified and the radio-frequency characteristics can be improved.

In the case where the multilayer coil component 1 according to the embodiment of the present disclosure is the 0603 size, the lengths of the first connection conductor 41 and the second connection conductor 42 preferably lie in a range from 15 μm to 45 μm and more preferably lie in a range from 15 μm to 30 μm .

In the case where the multilayer coil component 1 according to the embodiment of the present disclosure is the 0402 size, the lengths of the first connection conductor 41 and the second connection conductor 42 preferably lie in a range from 10 μm to 30 μm and more preferably lie in a range from 10 μm to 25 μm .

In the case where the multilayer coil component 1 according to the embodiment of the present disclosure is the 1005 size, the lengths of the first connection conductor 41 and the second connection conductor 42 preferably lie in a range from 25 μm to 75 μm and more preferably lie in a range from 25 μm to 50 μm .

It is preferable that the first connection conductor 41 and the second connection conductor 42 overlap the coil conductors 32 in a plan view from the stacking direction and be positioned closer to the mounting surface than the coil axis. The coil axis is an axis that passes through the center of the repeating shape formed by the coil conductors 32 and is parallel to the length direction.

Provided that via conductors forming a connection conductor overlap in a plan view from the stacking direction, the via conductors forming the connection conductor do not have to be precisely aligned in a straight line.

The width of the first connection conductor 41 and the width of the second connection conductor 42 preferably each lie in a range from 8% to 20% of the width of the multilayer body 10. The "width of the connection conductor" refers to the width of the narrowest part of the connection conductor. That is, when a connection conductor includes a land, the shape of the connection conductor is the shape obtained by removing the land.

13

In the case where the multilayer coil component 1 according to the embodiment of the present disclosure is the 0603 size, the widths of the connection conductors 41 and 42 preferably lie in a range from 30 μm to 60 μm .

In the case where the multilayer coil component 1 according to the embodiment of the present disclosure is the 0402 size, the widths of the connection conductors 41 and 42 preferably lie in a range from 20 μm to 40 μm .

In the case where the multilayer coil component 1 according to the embodiment of the present disclosure is the 1005 size, the widths of the connection conductors 41 and 42 preferably lie in a range from 40 μm to 100 μm .

In the multilayer coil component 1 according to the embodiment of the present disclosure, the lengths of the first connection conductor 41 and the second connection conductor 42 preferably lie in a range from 2.5% to 7.5% of the length of the multilayer body 10 and more preferably lie in a range from 2.5% to 5.0% of the length of the multilayer body 10.

In the multilayer coil component 1 according to the embodiment of the present disclosure, there may be two or more of the first connection conductor 41 and the second connection conductor 42. A case where there are two or more connection conductors indicates a state where a part of an outer electrode covering an end surface and the coil conductor facing that outer electrode are connected to each other in at least two places by the connection conductors.

Hereafter, an example of a method of manufacturing the multilayer coil component 1 according to the embodiment of the present disclosure will be described.

First, ceramic green sheets, which will form the insulating layers, are manufactured. For example, an organic binder such as a polyvinyl butyral resin, an organic solvent such as ethanol or toluene, and a dispersant are added to a ferrite material and the resulting mixture is kneaded to form a slurry. After that, ceramic green sheets having a thickness of around 12 μm are obtained using a method such as a doctor blade technique.

As a ferrite material, for example, iron, nickel, zinc and copper oxide raw materials are mixed together and calcined at 800° C. for one hour, pulverized using a ball mill, and dried, and a Ni—Zn—Cu ferrite raw material (oxide mixed powder) having an average particle diameter of about 2 μm can be obtained.

As a ceramic green sheet material, which will form the insulating layers, for example, a magnetic material such as a ferrite material, a nonmagnetic material such as a glass ceramic material, or a mixed material obtained by mixing a magnetic material and a nonmagnetic material can be used. When manufacturing ceramic green sheets using a ferrite material, in order to obtain a high L value (inductance), it is preferable to use a ferrite material having a composition consisting of Fe_2O_3 at 40 mol % to 49.5 mol %, ZnO at 5 mol % to 35 mol %, CuO at 4 mol % to 12 mol %, and the remainder consisting of NiO and trace amounts of additives (including inevitable impurities).

Via holes having a diameter of around 20 μm to 30 μm are formed by subjecting the manufactured ceramic green sheets to prescribed laser processing. The above-mentioned ceramic green sheets with via holes are processed by filling the via holes with a Ag paste. Then, prescribed coil-conductor conductor patterns having a thickness of around 11 μm are further screen-printed on the ceramic green sheets and dried. Then coil sheets are obtained. Conductor patterns corresponding to the coil conductors 32a, 32b, 32c, and 32d in FIG. 4 are printed as the coil-conductor conductor patterns.

14

The coil sheets are stacked in a prescribed order so that a coil having a coil axis in a direction parallel to the mounting surface is formed in the multilayer body after division into individual components. In addition, via sheets, in which via conductors that will form the connection conductors are formed, are stacked above and below the coil sheets.

The multilayer body is subjected to thermal pressure bonding in order to obtain a pressure-bonded body, and then the pressure-bonded body is cut into pieces of a predetermined chip size to obtain individual chips. The divided chips may be subjected to barrel polishing in order to round the corner portions and edge portions thereof.

Binder removal and firing is performed at a predetermined temperature and for a predetermined period of time, and fired bodies (multilayer bodies) having a built-in coil are obtained.

Each multilayer body is dipped at an angle in tank in which Ag paste has been spread to a predetermined thickness and baked to form a base electrode of an outer electrode on four surfaces (a main surface, an end surface, and both side surfaces) of the multilayer body. In the above-described method, the base electrode can be formed in one go in contrast to the case where the base electrode is formed separately on the main surface and the end surface of the multilayer body in two steps.

Formation of the outer electrodes is completed by sequentially forming a Ni film and a Sn film having predetermined thicknesses on the base electrodes by performing plating. A multilayer coil component according to an embodiment of the present disclosure can be manufactured as described above.

EXAMPLES

Hereafter, an example that illustrates the multilayer coil component 1 according to the embodiment of the present disclosure in a more specific manner will be described. The present disclosure is not limited to just the following example.

40 Manufacture of Test Pieces

Example 1

1. A ferrite material (calcined powder) having a prescribed composition was prepared.

2. A magnetic slurry was manufactured by adding an organic binder (polyvinyl butyral resin) and organic solvents (ethanol and toluene) to the calcined powder and putting the mixture into a pot mill along with PSZ balls and then sufficiently mixing and pulverizing the mixture in a wet state.

3. The magnetic slurry was molded into a sheet shape using a doctor blade method and then punched into rectangular shapes, thereby producing a plurality of ceramic green sheets having a thickness of 15 μm .

4. An inner-conductor conductive paste containing Ag powder and an organic vehicle was prepared.

5. Via Sheet Manufacture

Via holes were formed by irradiating prescribed locations on the ceramic green sheets with a laser. Via conductors were formed by filling the via holes with a conductive paste and land portions were formed by performing screen printing with a conductive paste in circular shapes around the peripheries of the via conductors.

6. Coil Sheet Manufacture

The coil sheets were obtained by forming via conductors by forming via holes in prescribed locations on the ceramic

green sheets and filling the via holes with a conductive paste, and then forming coil conductors by performing printing to form land portions and line portions.

7. Predetermined numbers of these sheets were stacked in the order illustrated in FIG. 3 and the resulting body was then heated, pressed, and cut into individual pieces using a dicer, and in this way, multilayer molded bodies were manufactured.

8. (Fired) multilayer bodies were manufactured by placing the multilayer molded bodies in a firing furnace, subjecting the bodies to a binder removal treatment under an air atmosphere at a temperature of 500° C. and then firing the bodies at a temperature of 900° C. The dimensions of thirty of the obtained multilayer bodies were measured using a micrometer, and the following average values were determined: L=0.60 mm, W=0.30 mm, and T=0.30 mm.

9. An outer-electrode conductive paste containing Ag powder and glass frit was poured into a coating film forming tank in order to form a coating film of a predetermined thickness. The places where the outer electrodes are to be formed on each multilayer body were immersed in the coating film.

10. After the immersion, each multilayer body was baked at a temperature of around 800° C. and in this way the base electrodes of the outer electrodes were formed.

11. Formation of the outer electrodes was completed by sequentially forming a Ni film and a Sn film on the base electrodes by performing electroplating. Test pieces of example 1 having the internal structure of the multilayer body 10 illustrated in FIG. 3 were manufactured as described above.

FIG. 6A is a schematic diagram illustrating the repeating shape of coil conductors of a test piece of example 1 and FIG. 6B is a schematic diagram illustrating the repeating shape of coil conductors of a test piece of comparative example 1. The repeating shape of the coil conductors of the test pieces of example 1 is a shape in which the number of coil conductors that are stacked in order to form one turn of the coil is two and in which the land portions are disposed in the upper half of the multilayer body 10 on the opposite side from the first main surface 13, as illustrated in FIG. 6A.

As illustrated in FIG. 6B, test pieces of comparative example 1 were manufactured by manufacturing multilayer molded bodies by manufacturing coil sheets for which the number of coil conductors that are stacked in order to form three turns of the coil is four and stacking the manufactured coil sheets. The repeating shape of the coil conductors of the test pieces of comparative example 1 is a shape in which the number of coil conductors that are stacked in order to form three turns of the coil is four and in which the land portions are disposed in both the upper half of the multilayer body on the opposite side from the first main surface and in the lower half of the multilayer body, as illustrated in FIG. 6B.

Measurement of Transmission Coefficient S21

FIG. 7 is a diagram schematically illustrating a method of measuring the transmission coefficient S21. In addition, FIG. 8 is a graph illustrating the transmission coefficient S21 in example 1 and comparative example 1. As illustrated in FIG. 7, a test piece (multilayer coil component 1) was soldered to a measurement jig 60 that was provided with a signal path 61 and a ground conductor 62. The first outer electrode 21 of the multilayer coil component 1 was connected to the signal path 61 and the second outer electrode 22 of the multilayer coil component 1 was connected to the ground conductor 62.

The transmission coefficient S21 was measured by obtaining the power of an input signal to the test piece and the

power of a transmitted signal from the test piece and changing the signal frequency using a network analyzer 63. The two ends of the signal path 61 are connected to the network analyzer 63. The transmission coefficient S21 indicates that the closer the transmission coefficient S21 is to 0 dB, the smaller the loss is.

It is clear from FIG. 8 that the resonant frequency is 64.1 GHz in example 1, the resonant frequency is 63.8 GHz in comparative example 1, and in the case of the configuration of example 1, the resonant frequency is shifted toward the high-frequency side, and better radio-frequency characteristics are realized.

While preferred embodiments of the disclosure have been described above, it is to be understood that variations and modifications will be apparent to those skilled in the art without departing from the scope and spirit of the disclosure. The scope of the disclosure, therefore, is to be determined solely by the following claims.

What is claimed is:

1. A multilayer coil component comprising:
a multilayer body that is formed by stacking a plurality of insulating layers on top of one another in a length direction and that has a coil built into the inside thereof; and
a first outer electrode and a second outer electrode that are electrically connected to the coil;
wherein the coil is formed by a plurality of coil conductors stacked in the length direction together with the insulating layers being electrically connected to each other,

the multilayer body has a first end surface and a second end surface, which face each other in the length direction, a first main surface and a second main surface, which face each other in a height direction perpendicular to the length direction, and a first side surface and a second side surface, which face each other in a width direction perpendicular to the length direction and the height direction,
the first outer electrode extends along and covers a portion of the first end surface and a portion of the first main surface,

the second outer electrode extends along and covers a portion of the second end surface and a portion of the first main surface,

the first main surface is a mounting surface,
a stacking direction of the multilayer body and an axial direction of the coil are parallel to the first main surface,

two coil conductors from the plurality of coil conductors that are stacked to define one turn of the coil,
each of the coil conductors from the plurality of coil conductors include a line portion and a land portion arranged at an end of the line portion, and the land portions of the coil conductors that are adjacent to each other in the stacking direction are connected to each other through via conductors, and

in a plan view from the width direction, the land portions are disposed in an upper half of the multilayer body on the opposite side from the first main surface.

2. The multilayer coil component according to claim 1, wherein the number of stacked coil conductors is in a range from 40 to 60.

3. The multilayer coil component according to claim 1, wherein a distance between coil conductors that are adjacent to each other in the stacking direction is in a range from 3 μm to 10 μm .

4. The multilayer coil component according to claim 1, wherein a length of a region in which the coil conductors are arranged in the stacking direction is in a range from 85% to 95% of a length of the multilayer body.

5. The multilayer coil component according to claim 2, 5 wherein a distance between coil conductors that are adjacent to each other in the stacking direction is in a range from 3 μm to 10 μm .

6. The multilayer coil component according to claim 2, 10 wherein a length of a region in which the coil conductors are arranged in the stacking direction is in a range from 85% to 95% of a length of the multilayer body.

7. The multilayer coil component according to claim 3, 15 wherein a length of a region in which the coil conductors are arranged in the stacking direction is in a range from 85% to 95% of a length of the multilayer body.

8. The multilayer coil component according to claim 5, 20 wherein a length of a region in which the coil conductors are arranged in the stacking direction is in a range from 85% to 95% of a length of the multilayer body.
